UNITED STATES PATENT OFFICE.

ARNO BOERNER, OF SCHEVENINGEN, NETHERLANDS, ASSIGNOR TO NAAMLOZE
VENNOOTSCHAP OCTROOI MAATSCHAPPIJ "HOLLAND" TOT EXPLOITATIE
VAN UITVINDINGEN, OF AMSTERDAM, NETHERLANDS, A COMPANY OF THE
NETHERLANDS.

GEM-GRINDING APPARATUS.

1,314,785.

Specification of Letters Patent.

Patented Sept. 2, 1919.

Application filed June 5, 1918. Serial No. 238,403.

To all whom it may concern:

Be it known that I, ARNO BOERNER, originally a subject of the Emperor of Germany, but having lost my nationality owing to the fact that I have resided outside of Germany for more than thirteen years without interruption and without ever giving notice to the German legations or consulates, residing at Scheveningen, the Netherlands, have invented certain new and useful Improvements in Gem-Grinding Apparatus, of which the following is a specification.

This invention relates to an apparatus for polishing diamonds and other precious stones and has for its object to provide an apparatus of this class in which by a simple adjustment quickly made pressure on the stone being cut, against the grinding medium, may be varied at will, and in which the jewel is so held that it may be inspected at any time by simply removing from the remainder of the apparatus the jewel holding member, which may be quickly returned, placing thereby the jewel in exactly the same position relatively to the grinding medium as it previously occupied.

The annexed drawings illustrate the invention; in these drawings: Figure 1 is a perspective view, Fig. 2 a side elevation, and Fig. 3 a plan view of a tool in accordance with the invention, Fig. 4 being a sectional view along A—A in Fig. 3.

The apparatus comprises a horizontal guide-piece 1 which is secured to a table (not shown) and provided with V-shaped external slide ribs 2, 2², along which a slide 3 is adapted to be displaced in a horizontal direction. The said slide 3 is provided with a knob 4 by which it may be displaced by hand and which has a screw connection with the slide, so that the latter may be secured in any desired position relative to the guide-piece 1.

The slide 3, in its turn, serves as a guide-piece for a second slide 5, and for this purpose it is provided at either side with a ridge 6, 6². In order that the slide 5 may always assume a fixed and predetermined position relative to the slide 3, its front end is provided with a hook or claw 7, which fits a wedge-shaped projection 8 of the slide 3. The said projection 8 has a recess 9 for re-

ceiving a pin 10 of the hook or claw 7, in such a manner, that the slide 5 always assumes a central position relative to the slide 3, even if there should be some clearance between the slide 5 and the ridges 6, 6².

The slide 5 carries a bracket 11 with bearings for a shaft 12 on which the tongs proper are rotatably mounted. The said tongs comprise two arms 13, 14, which are rotatable about the shaft 12 the one independent of the other; the arm 14 carries a laterally extending pin 15 which enters a slot 16 cut in the arm 13 concentrically with the shaft 12, in such a manner, that the arm 14, from the position shown in the drawing, may be pressed down without engaging the arm 13, while at a movement in the reverse direction the arms are coupled together.

The arm 14 has a somewhat enlarged right hand end portion, and secured to its bottom, is a plate 17 with a stub pin 18 for holding a coiled spring 19, whose bottom end is seated on a plate 20 with stub pin 21. The plate 20 is secured to a screw bolt 22 with a nut 23 located between two plates 24, 24² secured to the slide 5.

Pivots mounted within a slot 25 of the arm 14 is a pawl 26, which is provided with a handle 27 at its top, and having a projection 28 at its bottom end. When the arm 14 is pressed down, the said projection 28 is engaged by a projection 29 of the plate 24, whereby said arm is locked.

Vertically below the enlarged portion of the arm 14 a handle 30 is secured to the slide 5.

At the left hand side of the bracket 11 is a micrometer screw adapted to be raised and lowered by means of a nut 32. The top of said screw 31 is formed as a spherical head 33, adapted to be screwed up until it engages the bottom face of the arm 13 of the tongs.

The front end of the arm 13 carries a dop 34 for receiving one or a plurality of stones to be polished on the lapping wheel 35.

Secured to the rear portion of the arm 13 is a finger 36, which has an enlarged portion serving as a support for the thumb.

The operation of the device is as follows:

Assuming that the polisher has withdrawn the slide 5 with the parts attached thereto

from the slide 3 and that one or a plurality of stones have been set in the dop, also, that the arm 14 has been pressed down and that it is locked in this position owing to the coaction of the projections 28 and 29; the 5 polisher then replaces the slide 5 between the ridges 6, 6^a, until the hook 7 engages the projection 8, and the pin 10 contacts with the edges of the recess 9, during which operation he grasps the rear portion of the arm 14 with the palm of his hand, taking hold 10 of the handle 30 with his four fingers, his thumb pressing down the finger 36. The micrometer screw 31 should assume a position so as to allow the arm 13 to be supported 15 by the head 33 and the stone to be clear of the lap 35 if the polisher's thumb releases the finger 36. This being done, the micrometer screw may be turned down so far that the stone engages the lap 35 and, besides, 20 is free to descend through a distance required for the polishing of the particular facet to be cut. By exerting a suitable pressure on the handle 27 the polisher now releases the pawl 26, so that the coiled spring 25 19 forces the arm 14 upward and the latter transmits its pressure to the stone through the medium of the pin 15. The pressure of the stone on the lap may be adjusted by raising or lowering the supporting plate 20 by 30 means of the nut 23.

Should it be required for the stone to be positioned at a greater or at a smaller distance from the center of the lap, all that the 35 polisher has to do after having lifted the stone by means of the finger 36 and released the screw 4, is to displace the slide 3 in the required direction and through the correct distance, and then to secure it in its new 40 position.

Examining the progress of the work hardly takes any time. After the arm 14 has been pressed down against the action of the spring 19, and after it has been locked 45 by the pawl 26 (the stone being at the same time lifted clear of the lap by a pressure of the thumb on the finger 36), the polisher may withdraw the slide 5 from the slide 3 by moving it toward the center of the lap 35 and then lift it. Replacing the tongs in 50 their correct position is effected in a quite as simple manner; owing to the coaction of the hook 7 with the projection 8, the stone necessarily reassumes exactly the same position relative to the lap, and after the releasing of the pawl 26 the stone will exert 55 on the lap exactly the same pressure as before.

If the pressure of the stone on the lap is 60 to be increased or decreased to a very high degree, the coiled spring 19, which is loosely seated on the plates 17 and 20 and guided by the stub pins 18 and 21, may be removed and replaced by a stronger or a weaker one.

65 As a matter of course the apparatus de-

scribed above may be modified in various respects without the desired operation being interfered with.

What I claim as my invention and desire to secure by Letters Patent is:—

1. In apparatus of the class described, arms rotatably mounted on a shaft, means carried by one of the said arms for holding the stone to be polished, resilient means tending to impart upward movement to the second arm, means for locking the said second arm in the position in which it has moved through a certain angular distance against the action of said resilient means, and independent engaging elements on said arms adapted to permit downward movement of the second arm relatively to the first arm in one direction but to lock said arms together for simultaneous movement when said second arm is moved in the reverse direction. 70

2. In apparatus of the type referred to, a lever comprising two independent arms rotatably mounted on a shaft, means carried by one of the said lever arms for holding the stone to be polished, resilient means tending to impart upward movement to the second lever arm, and means whereby the second lever arm is adapted to move downward independent of the first lever arm, but to engage the latter on being moved in the reverse direction. 90

3. In apparatus of the type referred to, two arms rotatably mounted on a shaft, means carried by one of the arms for holding the stone to be polished, a coiled spring tending to impart upward movement to the second arm, means for adjusting the tension of said coiled spring, and means whereby the second arm is adapted to move downward independent of the first arm, but to engage the latter on being moved in the reverse direction. 100

4. In apparatus of the type referred to, two arms rotatably mounted on a shaft supported on a base plate, a slide on which the said base plate is adapted to be lengthwise displaced, a guide piece for said slide, means for securing the said slide in a predetermined position on the said guide piece, 110 means carried by one of the arms for holding the stone to be polished, resilient means tending to impart upward movement to the second arm, and means whereby the second arm is adapted to move downward independent of the first arm, but to engage the latter on being moved in the reverse direction. 115

5. In apparatus of the type referred to, two arms rotatably mounted on a shaft supported on a base plate, means carried by one of the arms for holding the stone to be polished, resilient means tending to impart upward movement to the second arm, a member secured to the first arm and extend- 125 130

ing alongside the second arm so as to be adapted to be engaged by the thumb of the operative when grasping the said second arm, and means whereby the second arm is adapted to move downward independent of the first arm, but to engage the latter on being moved in the reverse direction.

6. In apparatus of the type referred to, two arms rotatably mounted on a shaft supported on a base plate, means carried by one of the arms for holding the stone to be polished, resilient means tending to impart upward movement to the second arm, a member secured to the first arm and extending alongside the second arm, so as to be adapted to be engaged by the thumb of the operative when grasping the said second arm, a pawl rotatably mounted on the said second arm at the side of said member, a projection on the base plate adapted to coact with the said pawl, and means whereby the second arm is adapted to move downward independ-

ent of the first arm, but to engage the latter on being moved in the reverse direction.

7. In apparatus of the type referred to, two arms rotatably mounted on a shaft, means carried by one of the arms for holding the stone to be polished, a coiled spring tending to impart upward movement to the second arm, a slot in the first mentioned arm, a laterally extending pin on the second arm, the said pin being received in and coacting with the said slot in such a manner that the second arm is adapted to move downward independent of the first arm, but to engage the latter on being moved in the reverse direction.

In testimony whereof I have affixed my signature in presence of two witnesses.

ARNO BOERNER.
